Primary Examiner — Cynthia Ramirez*Assistant Examiner* — Michael Maharajh(74) *Attorney, Agent, or Firm* — Kirk A. Buhler; Buhler & Associates(57) **CLAIM**

The ornamental design for a locking cover for a valve, as shown and described.

DESCRIPTION

FIG. 1 is a top perspective view for a locking cover for a valve showing my new design;

FIG. 2 is a rear view thereof;

FIG. 3 is a front view thereof;

FIG. 4 is a top view, the bottom view being a mirror image thereof;

FIG. 5 is a left view, the right view being a mirror image thereof;

FIG. 6 is a left sectional view taken along lines **6-6** from FIG. 2 thereof; and,

FIG. 7 is an upper rear perspective view shown with the two parts separated.

The broken lines in FIG. 1 depict environmental subject matter of a lock for the invention and forms no part of the claimed design.
